UNITED STATES PATENT OFFICE.

ERNEST G. McCUALEY, OF DAYTON, OHIO, AND ARTHUR R. SMITH, OF FORT WAYNE, INDIANA.

RUDDER-CONTROL MECHANISM.

Application filed December 10, 1923. Serial No. 679,818.

To all whom it may concern:

Be it known that ERNEST G. McCUALEY and ARTHUR R. SMITH, citizens of the United States, residing at Dayton and Fort Wayne, respectively, in the counties of Montgomery and Allen and States of Ohio and Indiana, have invented certain new and useful Improvements in Rudder-Control Mechanism, of which the following is a specification.

This invention relates to a control mechanism, and more particularly to a rudder control bar operated by the feet of the pilot to control or adjust the rudder of an aircraft.

One object of this invention is to provide a flexible arrangement whereby the rudder bar may be adjusted so as to be resiliently held in a predetermined position with means being provided to adjust this position while in flight.

A second object is to provide a construction of this character with a means for quickly changing the predetermined position so that the rudder bar may be roughly adjusted to maintain any desired changes.

A further object is to provide a construction as just set forth with a further means adapted to be operated by the pilot's foot for making fine adjustments of the rudder bar so that the desired course of the aircraft may be exactly maintained.

By the construction as will be more fully set forth, a rudder control mechanism is provided which may be adjusted to counteract the turning and twisting effect on the aircraft due to the propeller having a tendency to cause the aircraft to move in the opposite direction to which the propeller is revolving or rotating. In addition to counteracting the propeller torque, the effect of the wind or air resistance against the same may be compensated for. It will therefore be seen that the resilient connection may be adjusted so that the rudder bar is resiliently maintained in a predetermined position so that a desired compass course may be maintained in flying from one destination to another.

Further objects will be more fully set forth in the accompanying description and claims, and in the drawings, in which:

Fig. 1, is a top plan view of the rudder bar control assembly.

Fig. 2 is a view in vertical longitudinal section of the same taken on line 2—2 of Fig. 1.

Fig. 3 is a vertical transverse section of Fig. 1 taken on line 3—3.

Referring more particularly to the drawings, a rudder bar 1 adapted to be operated by the pilot's feet is mounted free to rotate on a vertical pivot pin 2 by means of a bracket connection 3 which is secured to the rudder bar by welding or other suitable methods of construction. Integral with the rudder bar 1 is an eye bracket 4 mounted at each end of the rudder bar to provide means for the connection of cables 5 extending rearwardly to the rudder control surface.

Stirrups 6 are provided in order to enable the rudder bar to be operated by pushing or pulling by one foot if necessary and likewise to prevent the pilot's foot from slipping off the end of the rudder bar. A base or support 7 is provided upon which the rudder assembly is mounted. This support serves as a mounting for the pivot pin 2 by means of a flange bearing 8 attached to the support by rivets 9. The pivot pin 2 is free to slide vertically or to rotate within the bearing 8. The support 7 is adapted to be mounted in any suitable manner within the pilot's cockpit in the aircraft.

Upon the upper end of the pin 2 is a threaded portion adapted to receive a nut 10 to retain the bracket 3 in place. Pivot pin 2 is provided with a shoulder 11 constructed integral therewith. A member 12 is attached to each side of the rudder bar and forms a connection for a spring 13 attached thereto at one end, the other end of which is connected to an adjustable member 14 which is pivotally mounted upon the pin 2 between the shoulder 11 on the pin 2 and the bracket connection 3. This adjustable member 14 is provided with a bifurcated portion consisting of legs 15 and 16.

A frame member 17 is also mounted upon the pivot pin 2 so as to normally rotate thereon between the shoulder 11 and the support 7. This frame member is likewise provided with a plurality of legs 18 and 19 between which is mounted a threaded member 20, the ends of the member 20 being pinned or otherwise secured to the legs 18 and 19. Mounted upon this threaded mem-

ber 20 is a wheel 21 having internal threads adapted to engage with the threads on the member 20. This wheel 21 is provided with a roughened exterior surface which may take 5 the form as shown in Fig. 3 so that it may be rotated by a pawing motion of the operator's foot in order to cause an endwise movement of the wheel upon the member 20. This wheel 21 is adapted to be straddled by 10 the legs 15 and 16 of the adjustable member 14 in order to enable a relative movement of the member 14 and the frame member 17 about the axis of the pivot 2. Plates 22 are attached to the adjustment wheel 21 on each 15 side thereof to provide against wear on the legs 15 and 16 of member 14.

A foot lever 23 is pivotally connected to the pivot pin 2 by means of a clevis pin 24 and the end of this foot lever 23 is provided 20 with a bifurcated portion providing cam surfaces 25 and 26 adapted to bear against the lower portion of the flange bearing 8 so that when the lever 23 is pressed downwardly by the foot of the operator, the cam surfaces 25 and 26 bearing against the flange 8 cause a downward movement of the pivot pin 2. This downward motion of the pivot pin 2 causes the shoulder or flange 11 on the pin to clamp the frame member 17 tightly 30 against the upper surface of the support 7 so as to lock this supported in fixed position. The foot lever 23 may be released at any time by an upward movement of the same so as to permit free 35 rotation of the frame member 17 about the pivot pin 2.

When it is desired to set the rudder bar so as to be resiliently maintained in the desired position, the bar is operated by the 40 pilot's foot until the correct course is followed by the aircraft. The foot lever 23 is then pressed down by the pilot's foot so that the frame member 17 is held fixed. Such an operation also fixes the position of 45 the adjustable member 14 as this member cannot rotate about the pivot pin due to the position of the legs 15 and 16 which straddle the adjustment wheel 21. The springs 13 interconnecting the rudder bar and 50 the adjustable member 14 will therefore maintain the rudder bar resiliently in its adjusted position, by permitting movement of the same against the tension of these springs at any time. After adjustment of 55 the frame member 17, if the airplane slightly deviates from its desired course, a fine adjustment of the position of the rudder bar may be made by a pawing motion of the operator's foot so as to rotate the wheel 21 60 in order to cause a slight rotation of the adjustable member 14 about the pivot pin 2, the frame member being maintained clamped against the support in fixed position.

It will be seen that the adjustable mem-

ber 14 and frame member 17 together constitute a frame which is adjustably mounted on the pivot pin for adjusting the normal position of the rudder bar to any predetermined position and for resiliently holding the rudder bar in such predetermined position after adjustment. It will be understood that it is not necessary to have the adjustable frame formed in two parts or to have both a fine and a coarse adjustment 75 for resiliently locking the rudder bar in a predetermined position. It is not intended that our invention should be limited to the exact construction shown, but that the scope of our invention should be considered so as set forth in the following claims.

Having thus described our invention, we claim:

1. In a rudder control mechanism, a support, a rudder bar pivoted on said support, a member pivoted on said support, resilient means urging said bar to a predetermined position in relation to said member, and means for locking said member against pivotal movement on said support. 90

2. In a rudder control mechanism, a support, a rudder bar pivoted on said support, a frame member pivoted on said support, resilient means urging said bar to a predetermined position in relation to said frame member, means for locking said frame member against pivotal movement on said support, and means for adjusting the relation between the bar and the frame member. 95

3. In a rudder control mechanism, a fixed support, a rudder bar pivoted on said support, a frame adjustably mounted on said support, resilient means urging said rudder bar to a predetermined position in relation to said frame, and threaded means for adjusting the relation between the bar and the frame. 100

4. In an aircraft rudder control mechanism, in combination, a support, a pivotally mounted rudder bar, a pivot pin for said bar mounted in the support, means for resiliently holding said bar against pivotal movement, and foot operated mechanism for adjusting said last-named means. 110

5. In an aircraft rudder control mechanism, a combination of a pivotally mounted rudder bar, a support, a pivot pin for said bar mounted in said support, a frame adjustably mounted on said pin and connected to said rudder bar, and means for adjusting said pin longitudinally to clamp the frame and support together. 115

6. In an aircraft rudder control mechanism, a combination of a pivotally mounted rudder bar, a support, a pivot pin for said bar mounted in said support, a frame adjustably mounted on said pin, and resiliently connected to said rudder bar and cam means for adjusting said pin to clamp the frame and support together. 125

7. In an aircraft control mechanism, a combination of a pivotally mounted rudder bar, a support, a pivot pin for said bar mounted on said support, a frame adjustably mounted on said pin, resilient connection between said frame and said bar, means for adjusting said pin longitudinally to clamp the frame and support together and foot-operated means to adjust the said resilient connection.

8. In a rudder control mechanism for aircraft, a rudder bar, a support, a pivot pin for said rudder bar mounted on said support, a frame adjustably mounted on said pivot pin, means for locking said frame to said support, a member mounted on said pivot pin, resilient means connecting said member to said rudder bar, and an adjustable connection between said member and said frame.

9. In a rudder control mechanism for aircraft, a rudder bar, a support, a pivot pin for said rudder bar mounted on said support, a frame adjustably mounted on said pivot pin, a foot-operated lever for clamping said frame to said support, a member

pivotsly mounted on said pivot pin, a spring connecting each side of said rudder bar to said member and a wheel adapted to be turned by the operator's foot to cause small relative movements of said bar in relation to said frame.

10. In an aircraft rudder control mechanism, the combination of a pivotally mounted rudder bar, a pivot pin for said rudder bar movable longitudinally, means for resiliently holding the rudder bar against pivotal movement, and manually operable means for moving said pivot pin longitudinally for the purpose described.

11. In a steering mechanism for aircraft, a foot-operated control bar, resilient means for yieldingly holding said bar in a predetermined position and means manually operable while in flight to quickly lock and unlock said resilient means to quickly render said resilient means effective and ineffective on said control bar.

In testimony whereof we affix our signatures.

ERNEST G. McCUALEY.
ARTHUR R. SMITH.
